UNITED STATES PATENT OFFICE.

LAURENCE S. CARLETON AND ROBERT G. CARLETON, OF DAVENPORT, IOWA.

TRAFFIC-SIGNAL DEVICE.

Application filed December 20, 1921. Serial No. 523,724.

To all whom it may concern:

Be it known that we, LAURENCE S. CARLETON and ROBERT G. CARLETON, citizens of the United States, residing at Davenport, in the county of Scott and State of Iowa, have invented new and useful Improvements in Traffic Signal Devices, of which the following is a specification.

Our present invention pertains to traffic signals such as are employed for the purpose of designating the direction of travel of a motor vehicle or the like, and it contemplates the provision of a device through the medium of which a motor vehicle operator is enabled to indicate to vehicles or pedestrians either at his front or in his rear the direction he contemplates taking, and this with but a slight amount of effort on his part.

The invention further contemplates the provision of a signal for the purpose set forth, that will not only be applicable for use during the day time but is also constructed and arranged that it may be readily and efficiently employed at night time.

The invention in all of its details, will be fully understood from the following description and claims, when the same are read in connection with the drawings, accompanying and forming part of this specification, in which:

Figure 1 is a front elevation of my novel signaling device and showing the signal arm in various positions.

Figure 2 is a rear elevation of the device and showing the arms actuating wire or connection as properly adjusted to the shaft operating mechanism.

Figure 3 is a sectional view taken from the rear of the device and showing the various elements of the signal.

Figure 4 is a longitudinal sectional view of the signal.

Figure 5 is a detail view of the outer end of the signal arm and illustrating the illuminating elements thereof.

Similar numerals of reference designate corresponding parts in all of the views of the drawings.

Our novel device comprises a casing 1 that is provided flanged rim portion 1^a that is itself provided with a channel to receive a mirror 2^a whereby the device is adapted to serve for the purpose of permitting the driver of the vehicle to ascertain the condition of traffic at his rear.

The base 4 of our novel signal is fastened in any approved manner by preference on the left hand forward mud guard of the vehicle and the said base is provided with the housing 3 that is threaded or otherwise secured to the casing 2 as shown in Figure 4 and at the rear of the housing 3 I arrange a removable cover 5 whereby access may be readily obtained to the mechanism of the housing.

The base and its collar portion as well as the housing 3 are hollow and extending through the base is a cable or other suitable means 8 surrounded by the spring 9. The cable 8 is arranged in any position and manner adaptable to its purpose on the dashboard of the vehicle and preferably in convenient reach of the operator. The cable may be provided with a ring or handle in the discretion of the manufacturer and at its end that enters the housing 3 it is secured to the arm 7 of L-shaped form that in turn is fast on the shaft 6 that passes through the housing 3 and casing 1. Manifestly pull exerted on the cable 8 will in turn impart motion to the arm 7 and shaft 6. Downward pull of the cable 8 in one direction will operate the shaft in a similar direction and by pushing the cable in the opposite direction the shaft will also be rotated in the similar direction.

Secured to the inner end of the shaft 6 is an arm 10 that is connected by a link 21 to the body portion of a signal arm 14. A rivet 15 or other suitable means serves for the purpose of pivotally connecting the body portion 14 and link 21 to each other. At its lower end the arm 10 is provided with the integral portion 11 that is greatly increased in diameter toward its lower end and secured to the free end of the portion 11 are contacts 12 from which extend the wiring 13 to the illuminating bulb 17 of the outer end of the arm 16. These bulbs by preference are green and red respectively and are so arranged that they will be visible upon upward movement of the arm with respect to the casing.

Secured in the casing 1 is a member 19 provided with the posts to receive the wiring 20 that in turn passes through the portion 2 of the casing 1 and extends through housing 3 and support 9 and is connected with the battery or other ignition means of a motor vehicle. A shoe 18 is secured to the member 19 and is adapted on movement of the shaft 6 to contact with the members 12 to cause

the lights to glow. In the practical use of the invention, the base is secured to the left hand front fender of a motor vehicle with the mirror portion 2^a toward the driver 5 of the vehicle. When it is desired to indicate that the vehicle is about to be turned toward the right the cable 8 is pulled to its extreme limit, this will cause the arm 14 to assume the position shown in dotted lines at 10 the extreme upper end of Figure 1. This in turn will cause the contacts 12 at the lower end of 11 to be engaged by the shoe 18 to close the circuit and cause the green bulb 17 of the portion 16 of the arm 15 to glow. When the arm 14 is thrown to the position shown in full lines in Figure 1 to indicate a left hand turn this will cause the red light to glow, and when the arm is thrown to the lower position in dotted lines 20 in Figure 1 the red light also will be caused to glow. The green light wiring is only connected with the lower end of the contact points 12 of Figure 3. It will be seen by the drawing that the red light circuit is on 25 the first connection and its lights the light in the two lower positions red. The upper position is for the right hand turn and it alone has the green light. As above stated, the green light wiring being only connected with 30 the lower of the contact point 12 of Figure 3 and thus after the arm passes the position shown in dotted lines in the lower part of Figure 1, the shoe 18 will no longer engage this contact point but as the arm is forced 35 upwardly to indicate the dangerous right and left hand turns the shoe will continuously engage the lower contact point 12 shown in Figure 3, and cause red light to glow on these two positions.

40 It will be seen from Figure 3 that when the signal arm 14 is in its inoperative position the same will assume a compact position within the casing 1. It will further be seen that the wiring 13 to the lamp 17 extends 45 within the arm 14 and this not only protects the wiring but prevents the same from contacting with other elements of the device and thereby cause short circuiting.

It is our intention to construct the device 50 of aluminum as far as is practicable and especially the casing 1 and housing 3 thereof and when provided with the mirror 2^a it will be manifest that the device will add rather than detract from the finished appearance of the motor vehicle.

55

The device is furthermore so constructed and arranged that it is inexpensive to produce and maintain and comprises no delicate parts such as are liable to become inoperative after a short period of use and at the 60 same time it is adapted not only for use as a traffic direction signal but also for the purpose of enabling the operator to gauge the condition of traffic to his rear.

65

Having described our invention, what we 65 claim and desire to secure by Letters-Patent is:—

In a signal the combination of a support adapted to be secured to the rear portion of a vehicle, an interiorly hollow housing 70 formed integral on the support, a casing secured to the housing and being hollow throughout, a shaft that enters the housing and passes into the casing, an operating lever fastened to the shaft and movable therewith and having a bent end portion, a cable secured to the bent end portion; the casing having a slot formed in the peripheral edge thereof, an arm secured to the shaft within the casing, contacts arranged on one end of 80 the arm, a link secured to the arm, a signal arm secured to the link and movable into and out of the casing, wires that lead from the contacts on the arm to lamps that are arranged in the signal arm; said contacts being adapted to be engaged by a contact finger arranged in the housing when the signal arm is swung to operative position.

75

In testimony whereof we have hereunto set our hands in presence of two subscribing 90 witnesses.

LAURENCE S. CARLETON.
ROBERT G. CARLETON.
